UNITED STATES PATENT OFFICE.

ROBERT BACK AND GLENN A. COOPER, OF CHICAGO, ILLINOIS, ASSIGNORS TO THE WAHL COMPANY, OF CHICAGO, ILLINOIS, A CORPORATION OF DELAWARE.

DESIGN FOR A COMBINED DESK STAND AND PENHOLDER.

Application filed July 19, 1926. Serial No. 18,405. Term of patent 14 years.

To all whom it may concern:

Be it known that we, ROBERT BACK and GLENN A. COOPER, both citizens of the United States, residing at Chicago, in the county of Cook and State of Illinois, have invented a new, original, and ornamental Design for Combined Desk Stand and Penholder, of which the following is a specification, reference being had to the accompanying drawing, forming part thereof.

Fig. 1 is a perspective view of a combined desk stand and pen holder, showing my new design; and

Fig. 2 is a side elevation of the same.

We claim:

The ornamental design for a combined desk stand and penholder substantially as shown.

ROBERT BACK.
GLENN A. COOPER.
